DESIGN FOR A SPOON OR SIMILAR ARTICLE

Martin Laurence Millspaugh, Baltimore, Md., assignor to Samuel Kirk & Son, Incorporated, Baltimore, Md., a corporation of Maryland

Application July 1, 1940, Serial No. 93,380

Term of patent 14 years

To all whom it may concern:

Be it known that I, Martin Laurence Millspaugh, a citizen of the United States, residing at Baltimore, in the State of Maryland, have invented a new, original, and ornamental Design for a Spoon or Similar Article, of which the following is a specification, reference being had to the accompanying drawing, forming part thereof.

There is shown in the drawing, in

and in

I claim:

The ornamental design for a spoon or similar article, as shown.

MARTIN LAURENCE MILLSPAUGH.
